(57) **CLAIM**

The ornamental design for a flexible plastic bag with surface ornamentation, as shown and described.

DESCRIPTION

FIG. 1 is a perspective view of the flexible plastic bag with surface ornamentation showing our new design;

FIG. 2 is a front view thereof;

FIG. 3 is a rear view thereof;

FIG. 4 is a bottom view thereof;

FIG. 5 is a top view thereof;

FIG. 6 is a right view thereof; and,

FIG. 7 is a left view thereof.

The broken lines in the drawings are included for the purpose of illustrating environmental structure and forms no part of the claimed design. In FIGS. 1-2 and 4-7, the stippling indicates color contrast.
